UNITED STATES PATENT OFFICE

117,590

DESIGN FOR A PIPE COUPLING ELBOW

William R. Wilson, Detroit, Mich.

Application March 27, 1939, Serial No. 83,857

Term of patent 7 years

To all whom it may concern:

Be it known that I, William R. Wilson, a citizen of the United States, residing in Detroit, in the county of Wayne and State of Michigan, have invented a new, original, and ornamental Design for a Pipe Coupling Elbow, of which the following is a specification, reference being had to the accompanying drawing, forming a part thereof.

Figure 1 is a top plan view of a coupling elbow showing my new design;

Fig. 2 is a side-elevational view thereof;
Fig. 3 is a front elevational view thereof as seen from the left end of Fig. 2;

Fig. 4 is a rear elevational view thereof as seen from the right end of Fig. 2.

I claim:

The ornamental design for a pipe coupling elbow, substantially as shown.

WILLIAM R. WILSON.
